(57) **CLAIM**

The ornamental design for a garment bag, as shown and described.

DESCRIPTION

FIG. 1 is a top and front perspective view of a garment bag showing our new design according to a first embodiment; FIG. 2 is a front elevation view thereof;

FIG. 3 is a rear elevation thereof;

FIG. 4 is a left side elevation view thereof;

FIG. 5 is a right side elevation view thereof;

FIG. 6 is a top plan view thereof;

FIG. 7 is a bottom plan view thereof;

FIG. 8 is a top and front perspective view of a garment bag showing our new design according to a second embodiment; FIG. 9 is a front elevation view thereof;

FIG. 10 is a rear elevation thereof;

FIG. 11 is a left side elevation view thereof;

FIG. 12 is a right side elevation view thereof;

FIG. 13 is a top plan view thereof; and,

FIG. 14 is a bottom plan view thereof.

The dashed broken lines in the figures illustrate portions of the garment bag that form no part of the claimed design.
